PAGE 2

Fig. 3.

Fig. 4.

Fig. 5.

Fig. 6.

FIGURE 1 is a top plan view of a lawn sprinkler, showing our new design;

FIGURE 2 is a side elevational view thereof;

FIGURE 3 is a front elevational view thereof;

FIGURE 4 is a rear elevational view thereof;

FIGURE 5 is an enlarged, fragmentary sectional view taken along the line 5—5 of FIGURE 1; and

FIGURE 6 is an enlarged, fragmentary sectional view taken along the line 6—6 of FIGURE 2.

The dominant features of our new design are shown in solid lines.

We claim:

The ornamental design for a lawn sprinkler, as shown and described.
